UNITED STATES PATENT OFFICE

CHESTER ALFRED LINTON, OF KANSAS CITY, MISSOURI

SOUND AMPLIFIER

Application filed December 13, 1920. Serial No. 430,209.

This application is a modification of an earlier co-pending application for patent filed by me November 16, 1920, Serial No. 424,347, in which I show various modified forms each capable of many variations and modifications in structure while remaining within the spirit of my invention.

My invention relates to sound amplifiers and the like and particularly to means for improving the quality of sounds passing through sound amplifiers and the like having resonant walls or parts.

My invention concerns a novel means of focusing sounds at certain desired points on an acoustical apparatus by and through elastic or resonant means that may be solid or substantially solid.

It is particularly adapted for use in connection with the sound-box of a talking machine recorder or reproducer, but my invention is not limited to such type of device or machine but may be applied to other forms.

I have discovered that by outwardly connecting resonant bars or members or "sound conducting members" to different portions of a resonant amplifier or acoustical apparatus in such manner that longitudinally the bodies of the resonant bars or members or "sound conducting members" will be largely free from interference of the air vibrations inside the tubular passage of the amplifier or acoustical apparatus, the sounds passing through a resonant sound amplifier or acoustical apparatus may be regulated practically as desired. In my co-pending application referred to above, I show resonant bars or members or "sound conducting members" connected in an elevated manner to different portions of a sound amplifier or acoustical apparatus having a straight passage for sound, and by their use the quality and brilliancy of sounds were greatly improved.

I have further discovered that by connecting resonant bars or members or "sound conducting members" by one of their respective ends to predetermined places on a tubular throat portion of a sound amplifier or sound recorder and by connecting the other of their respective ends to a supplemental or co-operative amplifying or resonator member,

sounds passing through a tubular throat portion of a sound amplifier or sound recorder well be clarified with great facility and the distortion of sound caused by the curvature of a throat portion's walls will be lessened. I have discovered that sounds may thus be transmitted to or from a supplemental or co-operative member and, also, that such transmitted sounds help reinforce other sounds issuing from out an orifice of a tubular throat portion of a sound amplifier or sound recorder and thus provide a more life-like effect of sound coming from a large instrument like a piano or from a group of players.

One object of my present invention is to provide a novel compact arrangement of "sound conducting members" on an amplifier for sounds.

Another object of my invention is to provide novel improvements in a sound amplifier, by means of which sounds will be diffused.

Another object of my invention is to provide a supplemental or co-operative amplifying or resonator member or the like connected to a surface of an acoustical apparatus by suitable means that may be solid or substantially solid so that sounds may be recorded with greater facility and ease and many overtones that would otherwise be lost may be recorded on a suitable record.

Another object of this invention is to provide means for transmitting sounds to or from a sound amplifier or acoustical apparatus to or from a co-operative member whereby the sounds will not be distorted as they would be were they transmitted by purely air means.

Further objects of this invention are to provide means to help regulate the pitch of sounds that may be transmitted; to provide means for obtaining resultant tones; to provide a novel plurality of resonators; to provide an improved sound apparatus which will be of durable construction; and to provide other improvements as hereinafter set forth in the following specification and accompanying drawings, considered together or separately.

In the accompanying drawings,
Fig. 1 is a side elevation of a sound ampli-

fier, showing substantially solid "sound conducting members" or bars or members and showing a diaphragm or a supplemental or co-operative member above or adjacent.

5 Fig. 2 is a top view of the same, showing angular bars or members or "sound conducting members".

Fig. 3 is a front elevation of Fig. 1, showing curved walls of two resonators.

10 Fig. 4 is a cross section on the line 4—4 of Fig. 2, showing a circular throat formation and showing web attachments of solid or substantially solid bars or members or "sound conducting members".

15 To illustrate this modification of my invention, I annex hereto one sheet of drawings, in which similar reference characters are used to designate similar parts in the different views.

20 Numerous ideas have been carried out in this invention, with recognition on my part that one or more novel elements or combinations, etc., can be employed separately. One discovery portrayed in the invention is that 25 an element has certain latent potential vibratory or acoustic capabilities, and, furthermore, that when this idea is combined with structure having several elements,—say a plurality,—the latent yet workable potential 30 acoustic or vibratory capabilities are adapted for causal purposes or finite control, with most any useful result novel by any of these or like means, and either with minimum or maximum structure, possible. The point of 35 the application of force is not always material, as will become clear in this specification. Factors of stress are known herein relative with what is made apparent and of simple application when following the intent 40 of the description. The steps taken in the relationship of values of, or the comparative ratios of, elasticity, density, inertia, etc., of masses will be found of essence in understanding the interrelation or interdependence 45 of acoustic factors, altho an expert in the art should understand the revolutionary nature of the invention that makes use of the discovery of the relativity of acoustic factors for the production of a new result, or new 50 results. The invention is foreseen as alterable and adapted for mutation, on a large scale. Therefore, when viewed broadly, the drawing clearly shows relevant phenomena in a diaphragm, plate, or rod, or sliver, etc., 55 may be computed; and this marks a difference between this invention and the prior art.

In the drawings which illustrate my improvements as applied to a sound amplifier or the like, 1 designates the tubular resonator 60 or bell portion and 2 the tubular throat portion of the amplifier, or the like. These said portions are preferably of wood and, to provide an uninterrupted passage for sound, are, preferably, connected to adjacent ends, preferably by gluing or cementing. The ampli-

fier may, if desired, be suitably curved and of flaring or tapering form.

Inner surfaces of the tubular throat portion 2 and the tubular bell portion 1 are in this instance provided with a hard coating, 70 such as asphaltum or the like, this coating being, preferably, pumicated or sanded or roughened or the like to remove the glazed surface. This hard surface, thus treated, effects the best results. If desired the hard coating, such as asphaltum or the like, may be placed upon one or more coatings of varnish on the inner surfaces of the sound amplifier, or on the inner surfaces of the portions 1 and 2, and, also, if desired, upon one or 80 more coatings of varnish on the outer and rear sides of the tubular throat portion 2. Good results are attained without any coating in construction, therefore coating material of any kind may be dispensed with if 85 preferred.

For increasing the purity of the sound waves and for adding new frequencies over tone effects I provide at opposite sides of the sound amplifier a number of "sound conducting members" or resonant bars, each plurality of which may consist of an inner body 3 and an outer body 4. The ends of the bodies 3 and 4 are in this instance respectively connected, preferably by gluing or 90 cementing, to the outside of the walls of the bell portion 1 and the tubular throat portion 2, as shown in Fig. 2.

In the arrangement selected for illustration, the bodies 3 and 4 of each plurality of "sound conducting members" or resonant bars are of substantial area in cross section and preferably of determined frequency and are connected to each other by a relatively thin resilient longitudinal web or membrane 100 or the like 5, as shown in the cross sectional view in Fig. 4. Each body 3 is suitably connected by the edges of a relatively thin resilient longitudinal web 6 to the outside of the walls of the said portions 1 and 2 of the sound amplifier or recorder. The preferred arrangement of the web or membrane or the like 6 is shown in the cross sectional view in Fig. 4 selected for illustration of the principle employed. These webs may, if desired, be curved and in the same plane or curved longitudinally or horizontally or in any position in keeping within the broad scope of this invention.

For conducting sound vibrations from the tubular throat portion 2 to the tubular bell portion 1, there is also preferably provided a "sound conducting member" or resonant bar or member comprising a substantial body portion 7, the ends of which are respectively connected, as by gluing or cementing, to in this instance an upper side of the tubular bell portion 1 and to a forward side of the throat portion 2. A relatively thin longitudinal web or membrane or the

like 8 which may be substantially rigid and vertical if desired may be arranged to form a connection between the body portion 7 and an upper side of the tubular bell portion 1 5 and a forward side of the tubular throat portion 2. Any impulse traveling through solids such as compose the member 7 and the element 2 may vibrate said web from opposite sides simultaneously. The body portion 7 10 and the web 8, when employed in the form shown, may serve the further purpose of firmly uniting the said portions 1 and 2.

For sympathetic vibration or for rendering audible the sound waves from a suitable 15 source, there may be provided a diaphragm or a supplemental or co-operative member having a thin wall or walls and comprising in this instance a concave or bell member 9 of circular form, which has in this instance 20 an orifice or its open end facing in the same general direction as the tubular bell portion 1 and which has in this instance its closed end pointed in a general direction toward the tubular throat portion 2. It is 25 obvious the relative positions of the members named may be varied. A method and means are being illustrated and the description in general and the drawing used in conjunction therewith are not intended for limiting pur- 30 poses, but for making obvious and plain a revolutionary invention. The bell member 9 may be and, in the form shown is, prefer- 35 ably, connected to and supported by a "sound conducting member" 10, which is pref- 40 erably attached firmly to the said member 9 and the said portion 1 adjacent the forward ends thereof. When supported in this way, the wall of the member 9 will be at an angle to a wall of the bell 1 and allow of sound 45 reflection and sound interference in the air space between said walls.

A plurality of suitably directed and, in this example, forwardly converging resonant members or bars or "sound conducting members" 11 and 12, which may be composed, as shown, of bent sound-boards or similar vibratory elements and are raised bridge-like in air space, have their rear ends respectively connected to opposite walls of 50 the tubular throat portion 2 preferably to the outside surfaces thereof and relative to the natural frequency thereof. The forward ends of the resonant bars or "sound conducting members" 11 and 12 are, preferably, 55 respectively connected to opposite sides of the supplemental or co-operative bell member 9 adjacent its center or resonance peaks therein, or to introduce a tuned strain therein, for purposes of controlling nodal lines 60 or values, as shown in Fig. 2.

It may as well be noted here that it is best to have the relative proportions of the parts with which to effect selection of the frequencies desired in said resonator, or bell mem- 65 ber, or the like. One of the advantages of

this arrangement of resonance is that it is applicable to vibrating systems in which the amplitude of the vibrating members is at times quite small. The members 11 and 12 are preferably in association and of like 70 structure and of approximately equal length.

It is clear this acoustical device may employ a diaphragm in any suitable manner and relative therewith a plurality of acoustically scaled and balanced vibratory means, and the 75 rate of frequency of any or every part of the device, or a modification thereof, may be of computed phase relation relative with the frequency employed. As illustrated in Fig. 80 3, the bell member 9 is, preferably, small in comparison with the main amplifying or bell portion 1 but it may be of equal size or larger and its shape and form and acoustic surface resistance may be determined by experiment.

All or desired parts of the walls of the 85 tubular bell portion 1 and the tubular throat portion 2 being resonant and the walls of the co-operative bell member 9 being resilient or resonant and the members or bars 11 and 12 being resilient or re- 90 sonant and the "sound conducting members" or bars 3, 4 and 7 with their respective webs being resilient or resonant, sound vibrations will be transmitted from the throat portion 2 to the tubular bell portion 1 and the 95 co-operative bell member 9 by the "sound conducting members" or bars in a novel manner partly or largely independent as the case may be to the vibrations which pass directly through the air in the throat portion 2 and 100 the bell portion 1. By means of operable parts of this arrangement as shown, for example, a special result may be attained; or with certain combinations of the elements new over tones are delivered to the listener, 105 the form of sound waves is changed, the effective acoustic range of frequencies is in- 110 creased, and the amplified sounds coming from a suitable source are clearer and more natural than without the use of the different units or of the "sound conducting members" 115 or bars and the co-operative bell member 9, when one form of the device, for example, is used in connection with a sound-box of a talking machine reproducer or the like.

When an amplifier or acoustical apparatus constructed in accordance with one form of this invention is used for transmitting sounds to a recording medium, the sounds received at said medium are clearer, more 120 natural and of different wave form and period than would be the case if the "sound conducting members" or bars, were not used. The employment of the device therefore enables the production of a superior record.

While, in the scientific sense, sound is prop- 125 agated like one ball hitting another, (a jarring process, I might say) I want it understood I do not limit my invention by the use of the words or terms "sound conducting 130

member" or "sound conducting means" or similar words or terms of similar meaning.

In applying this invention the particular form to be used in any case to give the best results may be determined experimentally. The drawings are not in scale and therefore are not to be taken as shop drawings. I have proved by experimenting with this invention that a small periodic force is continued long enough may set my resonant bars or boards or "sound conducting members" vibrating forcibly if the free period of the resonant bars or boards or "sound conducting members" coincides or nearly coincides with the period of the force. Equivalent substances of stress may be employed instead of resonant substances where found interchangeable in any part of the device, or in any modification thereof.

While a certain number of resonant members or "sound conducting means" produces a different result than by the employment of a less number, I want it understood that I do not limit my invention to a certain number of resonant members or sound conducting means, for the obvious reason that different people have different tastes for music and demand different tone qualities. I desire to connect the resonant bars or members or "sound conducting members" 3 and 4 at forward points longitudinally on the sound amplifier or sound apparatus, but I do not wish to limit myself or invention to connections made only in that manner.

The length, width and thickness and the volume elasticity and density of the resonant members or "sound conducting members" 3, 4 and 7, with their respective webs, and 11 and 12, have a direct relation to the desired pitch of the tone and the volume of sound transmitted. In other words, the kind or sort of a member employed in construction, or in a modification thereof, effects the result obtained. Amplifiers for recording and reproducing sound that are of different sizes and shapes and of different wall thicknesses may require one or more "sound conducting members" or resonant bars or members of different shapes, lengths, widths or any one or more or thicknesses or all four differences, including differences in volume elasticity and density. Nor do I limit my invention to a "sound conducting member" or members or bars made of wood; any good stable substance that may conduct or influence sound, when connected properly, in an advantageous manner may be used.

I do not desire to be limited or restricted to any particular substance employed for the web or membrane 8 or the webs or membranes 5 and 6, as any particular web or membrane may be of any suitable substance, as the case requires. Nor do I desire to be limited to any particular size or shape or elasticity, or the equivalent of elasticity, of

the web or membrane employed, for the modifications of this invention as shown and argued in co-pending application for patent may be numerous and of varied form. Therefore the web or membrane may be of any shape or tension or curvature, etc.

While I have shown only two resonant members or bars or "sound conducting members" connected to a vibratory body or tube or to the tubular throat portion of the sound amplifier and connected to a diaphragm or to a co-operative resonator member, yet I do not desire to limit my invention to a given number of members or bars or "sound conducting members" so connected, for the obvious reason that the principle and method of transmitting sound vibration to or from vibratory bodies or to or from a sound amplifier or recorder and to or from an auxiliary member or the like is herein shown and described. Although different results are produced by a larger number of resonant bars or member or "sound conducting members" connected at places which may be predetermined on the sound amplifier, I do not want the use of the word "predetermined" to limit this invention in any way.

Nor do I limit or restrict this invention to resonant bars or members that are merely glued or cemented to a surface of an acoustical apparatus or sound amplifier. The resonant bars or members or "sound conducting members" may be fastened on as integral parts or otherwise, as may be deemed expedient.

Nor do I want it understood that I limit my invention to a sound amplifier or sound recorder made of wood; any good resonant substance formed integrally or otherwise may be used and with satisfactory results. I also wish it to be understood that the several features of this invention may be used either singly or collectively without departing from the scope of the claims.

I realize that many modifications of this invention are possible, therefore I say my invention is not limited to these particular constructions shown and described and it is my intention to cover all other modifications which may be made without departing from the spirit of my invention or the scope of the claims.

What I claim as new, and desire to secure by Letters Patent of the United States, is, as follows:

1. A sound amplifier comprising a tubular throat portion having resonant walls adapted to convey sound to or from a reproducing means, a small sound resonator a distance apart, and suitable sound conducting means connecting said small sound resonator and a surface of said tubular throat portion.

2. A sound amplifier comprising a tubular throat having resonant walls adapted to conduct sound to or from a sound-box, a sound

amplifying member a distance apart, and a plurality of suitable resonant members connecting said resonant walls outwardly to said sound amplifying member.

5. A sound amplifier, or the like, comprising a tubular member having resonant walls directly adapted to transmit sound to or from a sound source, a co-operative bell member supported apart from said walls, and 70 sound transmitting means firmly secured to a surface of said resonant walls and firmly secured to said co-operative bell member.

10. In combination with a resonator, a supplemental amplifying member a distance apart provided with a single orifice said supplemental amplifying member having a plurality of sound conducting members extending away therefrom.

15. A sound amplifier comprising a tubular throat portion and a tubular bell portion connected at adjacent ends and forming a curved passage for sounds, a supplemental amplifying member having comparatively thin walls, said walls being resonant, and 80 outward sound transmitting means attached to said tubular throat portion on approximately opposite sides thereof, said sound transmitting means being elevated bridge-like approximately side by side and connecting said 85 supplemental amplifying member to said tubular throat portion.

20. In a sound amplifier provided with a tubular passage for sounds, said tubular passage having resonant walls provided with an inlet and an outlet, a supplemental member having resonant walls, and elevated sound conducting means having predetermined lengths, widths and thicknesses to help regulate the pitch and volume of sound transmitted to said supplemental member, and said sound conducting means firmly attached to said resonant walls of said tubular passage and having an elasticity and density similar in kind to the elasticity and density of said 100 resonant walls of said tubular passage.

25. In combination with a sound amplifier a supplemental member having resonant walls and individual angular resonant bars of elevated structure, said bars being symmetrical and largely of uniform cross section throughout their major lengths, said bars having tapered ends, each of said bars having a length, width, thickness, volume elasticity and density which may be predetermined to help regulate the pitch of sounds 110 passing through said amplifier and through said resonant bars, said resonant bars having a natural period of vibration adapted to harmonize with the natural period of vibration.

30. A sound amplifier including a longitudinal curved resonant tube and a separate bell member having resonant curved walls and a raised resonant member extending from an exterior surface of said tube and connected to said walls of said bell member to introduce a tuned strain therein.

35. A sound amplifier comprising a tubular throat portion and a tubular resonator portion arranged to transmit sound from one to the other, said tubular portions having reso-

nant walls, and a resonant member having a substantial body portion projecting away from said tubular portions, the ends of said body portion being respectively connected a distance from each other to the walls of said tubular portions, and a thin web connecting said body portion with the walls of said tubular portions, thereby to produce a different composition of the sound.

4. In combination with a resonator, a supplemental amplifying member a distance apart provided with a single orifice said supplemental amplifying member having a given length to help regulate the pitch of sound transmitted through said body portion, the ends of said body portion being respectively connected to the walls of said tubular passage, and a thin web connecting said body portion with the walls of said tubular passage thereby increasing the volume of sound by utilizing its energy in having sympathetic vibration in said body portion and in said web.

90. In an amplifying device, the combination with a tubular throat portion, of a resonator having thin walls, and a series of resonant sounding boards separated a slight distance from each other by thin webs and arranged in substantially parallel planes, and means for connecting the outer and inner ends of said boards securely, said boards being supported at one of their respective ends by said tubular throat portion and at the other of their respective ends by the said thin walls of said resonator, and said series including outer boards long compared to inner boards in the series.

100. In a sound reproducing device adapted for introducing sympathetic vibration in a desired volume in a resonator having a closed end, a method of controlling the vibratory effects delivered to said resonator which consists in having elevated vibratory spaced means connected to said resonator relative to the natural frequency thereof and capable of delivering to said resonator frequencies of sound different than directly impressed at the opposite ends of said means and of having the relative proportions of the parts with which to effect selection of the frequencies desired in said resonator.

110. A sound amplifier including a longitudinally curved resonant tube and a separate bell member having resonant curved walls and a raised resonant member extending from an exterior surface of said tube and connected to said walls of said bell member to introduce a tuned strain therein.

125. In a sound amplifier like an acoustical apparatus for a talking machine or similar inventions, resonant walls forming a sound orifice resonator member supported beside said orifice, and a sidewise homogeneous member extending from said walls to said 130

- resonator member, said sidewise homogeneous member being proportioned to influence sound impulses in said resonator member.
14. A sound amplifier having a resonant portion and an adjacent bell member having resonant walls of determined natural frequency, and in combination therewith means for conducting sound impulses from said resonant portion to said bell member, said means adapted to deliver sounds of determined frequency relative to the frequency of the sounds progressing through said resonant portion when in operation, the middle portions of said means being free to vibrate. 70
15. In combination in a sound device, a hollow body, webs, and resilient members, said members being secured to said hollow body, and at least one of said members being secured to said webs. 80
16. In combination in a sound device, a resonator, and members having webs, said members being secured in spaced acoustic relation to said resonator and to said webs. 85
17. A sound amplifier comprising a curved tubular body, and an outside resonator, said tubular body having a portion connected transversely to said resonator, said tubular body and said resonator having walls of response frequencies arrived at by comparison with what is necessary for a true simulation of the original sounds, said tubular body and said resonator being acoustically a unit. 95
18. A sound amplifier comprising a tubular body adapted for direct communication with a sound box, adjacent resonators connected to said tubular body, one of said resonators being closed at one of its ends. 100
19. In a sound device, the combination with a bell member adapted to be in direct communication with a sound box, of a resonator exteriorly adjacent said bell member and in secure connection therewith, said resonator having one wall at an angle to a wall of said bell member, for purposes of sound reflection and sound interference. 105
20. An acoustical apparatus consisting of spaced connected bell members, each of said bell members provided with means projecting therefrom for effectively controlling at a plurality of points the frequency peaks therein. 110
21. In an acoustical apparatus for a talking machine, a vibratory member, and a thin circular resonant body concave from its center, sound transmitting means between said member and said body and connected to said member, said means comprising a plurality of exterior raised spaced vibratory members of like structure and of approximately equal length, said means being secured to said body in a manner whereby resonance peaks adjacent said center will be controlled. 120
22. In combination in a sound reproducing device, a resonant body having an orifice and a plurality of outside raised fairly elastic members connected to spaced apart places on said body, for purposes of controlling resonance peaks in said body, and the device as claimed adapted for response to vibratory impulses from a suitable source. 125
23. A sound amplifier comprising a hollow body, an elastic web secured thereto, said web having a structure shape and dimensions such that it is capable of responding with the exact amplitudes of sound desired in a particular instance, said hollow body being adapted to longitudinally vibrate said web in the direction of the length of said hollow body, when the latter is vibrated by suitable means. 130
24. An acoustical device, comprising a body, an elastic web secured to said body, said web having a density elasticity and inertia directly relative with the associated structure and the use for which it is employed and is thus adapted for responding with the particular frequencies of sound desired, said body being adapted to vibrate said web in the direction of its width by the sides of said web. 135
25. A sound amplifier for a reproducing device, comprising vibratory members that are essentially adapted for the transmission of desired vibrations of sound, each of said members having a particular response frequency, said members having an elastic web connected therebetween, said web having a particular natural free period of vibration, for the primary purpose of obtaining novel effective resonance response in said web. 140
26. A method of transmitting sound vibrations through a web body; which consists in having a web of required elasticity and of desired shape and size and of having vibratory means connected alongside the major part of the edge of said web, said vibratory means having per lineal inch of said web the natural frequency required, and said vibratory means adapted to impart the necessary forced frequencies whereby said web will vibrate throughout substantially as desired when in operation. 145
27. An acoustical device comprising a diaphragm and vibratory members of computed phase relation when in connection therewith, said members being attached to said diaphragm, whereby resonant peaks in said diaphragm will be under finite control. 150
28. An alterable acoustic device comprising a diaphragm and a vibratory member attached to an edge thereof, said member capable of being tuned relative with the possible overtones that can be delivered by said diaphragm, for the purpose of obtaining the most complete range of overtones thereby. 155
29. An acoustical device comprising a diaphragm and relative therewith a plurality of acoustically scaled and balanced vibratory means, said means respectively connected by 160

their ends to points on said diaphragm equidistant from each other, the necessary remaining acoustic factors being taken into consideration in the construction of the device.

5 30. A sound amplifier for a reproducing device, comprising resonant elements of equal kind opposite each other and having an elastic web of determined frequency therebetween, for purposes of vibrating said web from opposite sides simultaneously.

10 31. A sound amplifier comprising sound conducting means having a web connected therebetween, said means being adapted to deliver vibratory impulses varying from each other, said means having structures adapted to alter the vibratory impulses that can be delivered to said web, substantially as set forth.

15 32. A sound amplifier comprising a tube, a web curved to follow the contour of said tube, and a sound conveying member, said member connected to both said tube and said web and adapted to vibrate said tube and said web under the influence of sound.

20 33. A sound amplifier adapted to be connected to sound reproducing means and comprising a hollow body provided with a plurality of elastic webs on opposite sides thereof and longitudinally thereof, said webs being adapted to vibrate in sympathy with said hollow body, said webs having periods of frequency needed for a full rendition of the tones and overtones prefigured in construction and accomplished by the use of the device.

25 34. An acoustic device comprising a diaphragm member adapted to be firmly held by a part thereof, and a vibratory member of computed stress attached to one point of said diaphragm, the members when in connection being relative with the desired rate of frequency of said point of said diaphragm and relative with the computed potential and desired frequencies of said diaphragm and relative with various tested points on said diaphragm when at least one of these said tested points is acoustically connected with a source of sound.

30 35. An acoustical device comprising diaphragm means and interconnected vibratory means adapted for free vibration, the latter means being connected with said diaphragm means in an opposed manner, said interconnected means being of alterable nature, and said diaphragm means and said interconnected means having masses and forms of computed values one with another, so that the phase relations, one with another, of different parts of said diaphragm means are restricted when subject to a given frequency and so that said diaphragm means shall vibrate in the exact manner required.

35 36. The method of introducing new frequencies from a source of sound in a dia-

phragm, which comprises contact means for transmitting a given amount of vibration to said diaphragm, of having adjacent said means a computed point of stress in said diaphragm dependent on an element connected therewith, and of having a computed mass of said diaphragm adapted to transmit a given amount of vibratory energy across said point of stress and in computed phase relation therewith, and of having the several masses selected with regard for their acoustic structural interdependence and their collective ability to respond and react in a given acoustic design.

40 In testimony whereof I have signed my name to this specification.
